UNITED STATES PATENT OFFICE.

EDWARD DUDLEY LEWIS, OF ELMIRA, NEW YORK.

COMBINED MUFFLER AND AIR-HEATER.

1,003,620.

Specification of Letters Patent. Patented Sept. 19, 1911.

Application filed April 18, 1910. Serial No. 556,264.

To all whom it may concern:

Be it known that I, EDWARD D. LEWIS, a citizen of the United States, residing at Elmira, in the county of Chemung and State 5 of New York, have invented certain new and useful Improvements in a Combined Muffler and Air-Heater; and I do declare the following to be a full, clear, and exact description of the invention, such as will 10 enable others skilled in the art to which it appertains to make and use the same.

This invention relates to combined mufflers and air heaters for gasoline engines.

The object of the invention is to provide 15 an improved construction of muffler for gasoline or similar forms of engines whereby the exhaust from the engine in passing through the muffler is utilized for heating purposes.

20 With the foregoing and other objects in view, the invention consists of certain novel features of construction, combination and arrangement of parts as will be more fully described and particularly pointed out in 25 the appended claims.

In the accompanying drawings: Figure 1 is a vertical longitudinal section of a combined muffler and heater constructed in accordance with the invention and showing 30 the manner in which the heated air from the muffler may be utilized. Fig. 2 is a vertical section on the line 2—2 of Fig. 1; and, Fig. 3 is a vertical view through one of the muffler sections taken on the line 3—3 of 35 Fig. 1, and showing the construction of the baffle plate arranged therein.

In the practical embodiment of the invention I provide an air chamber 1 which is preferably constructed in the form of a 40 sheet metal cylinder closed by heads 2 and bound or covered on its outer side with an asbestos wrapping 3, one of the heads 2 being provided with an air inlet opening 2^a, this end of the cylinder being hereinafter 45 referred to as the open end. In one side of the cylinder 1 adjacent to its closed end is formed an air outlet or discharge passage 4 provided with a threaded nipple 5. With the nipple 5 is connected a T or other form 50 of branch coupling 6 to the branches of which are connected air conducting pipes 7 which extend to any desired point for discharging the air from the cylinder and are preferably connected at their point of

discharge with suitable registers which may 55 be set into a floor or wall. The register 8 is here shown as being provided with a cap 9 for closing or regulating the opening thereof, said cap having formed on its under side spring fingers 10 having beveled catches 11 60 formed on their inner ends said catches being adapted to be engaged with a series of teeth or notches 12 formed on the inner sides of the register whereby the cap 9 may be supported at the desired elevation above 65 the opening in the register. In the register are also provided stop shoulders 13 which are adapted to be engaged by the catches 11 thus preventing the cap from being disengaged from the register. The cap 9 is 70 preferably provided with a chain 14 having on its end a ring 15 whereby the cap may be conveniently raised when desired.

Arranged in the cylinder 1 is an exhaust muffler comprising a series of hollow sections 16 which are connected together at their center by tubular coupling members 17 the ends of which are inserted through and clenched or riveted into engagement with the adjacent sides of the muffler sections as shown. The end section of the muffler at each end of the cylinder 1 is provided with a threaded nipple 18 which is inserted through the head 2 of the cylinder and is provided with a jam nut 19 for 80 securing the sections to the cylinder. Each of the sections 16 of the muffler is formed in two parts having on their outer edges flanges 20 which when the parts are engaged are riveted together to hold the parts 90 in position thus forming the hollow sections of the muffler. Arranged in the center of the sections and secured at their outer edges between the parts of the sections are baffle plates 21 in which adjacent to their 95 outer edges is formed an annular series of passages 22 through which the exhaust gases pass from one part of the muffler sections to the other. The baffle plates 21 are pressed outwardly to a point at their centers thus forming a projection which extends in the direction from which the exhaust is coming and serves to deflect the exhaust gases toward the apertures around the outer edges of the plates as indicated 100 by the arrows in Fig. 1 of the drawings. The riveted flanges of the muffler sections are cut away to form air passages 23 said

passages being arranged at diametrically opposite points in the consecutive or adjoining sections so that a circuitous or tortuous passage is formed through the cylinder which will cause a thorough circulation of the air around and between the muffler sections thereby heating the air by its contact with said sections, the latter being kept hot by the passage of the exhaust gases there-through, said gases being caused to thoroughly circulate through each of the sections by means of the baffle plates and passages therein before passing through the couplings 17 into the next muffler section. 10 The air to be heated enters through the open end of the cylinder and passes through the same in the manner described and is discharged through the port 4 and nipple 5 into the heat conducting pipes 7 by which it is conveyed to the registers and discharged into the rooms or compartments to be heated. The exhaust from the engine enters the center of the first muffler section at the open end of the cylinder 15 through a suitable connecting nipple provided to receive the exhaust conducting pipe from the engine and passes through the entire series of sections and is discharged through the nipple 18 on the last muffler section at the closed end of the cylinder as indicated by the arrows in Fig. 1 of the drawings.

From the foregoing description taken in connection with the accompanying drawings, the construction and operation of the invention will be readily understood without requiring a more extended explanation.

Various changes in the form, proportion and the minor details of construction may 40 be resorted to without departing from the principle or sacrificing any of the advantages of this invention as defined in the appended claims.

Having thus described my invention 45 what I claim is:

1. A heater comprising, an outer casing having an inlet at one end and an outlet at the other end, intercommunicating hollow sections arranged transversely of the 50 said casing and having flanged edges in contact therewith, said flanges having openings out of alinement with each other, thereby forming a tortuous air passage; the end hollow sections being provided with 55 an inlet and an outlet respectively for the heating medium.

2. A heater comprising an outer casing having an inlet at one end and an outlet at the other, intercommunicating hollow 60 sections arranged transversely of and closely fitting the interior of the said casing and each formed of two oppositely disposed centrally perforated concave members having flanged edges and a baffle- 65 plate located between said members, perfo-

rated beyond its center and united at its margin to the flanges of said concave members; the outer margins of the hollow sections thus formed having openings out of alinement with each other to form a tortuous air passage; the end hollow sections being provided with an inlet and an outlet respectively for the heating medium. 70

3. In a combined muffler and air heater, a casing having an air inlet opening at one end and an air outlet opening adjacent its opposite end, and an air conducting pipe communicating with the outlet opening, a series of hollow muffler sections arranged in said casing, each of said sections comprising two oppositely disposed substantially similar connected portions having flanged edges adapted to contact with the inner periphery of the cylinder, each of said sections being provided with an air 80 passage through said flanged edges, the passage of each section being arranged at a diametrically opposite point from the passage of the contiguous sections whereby a circuitous air passage is formed through 90 the casing around said sections, one end section having an inlet for exhaust gas and the opposite end section having an outlet for the same, baffle plates secured in said sections between the oppositely disposed 95 portions, said plates having formed therein a series of passages, means upon each of said plates whereby the exhaust gases entering the sections are deflected toward the 100 passages in said plates, and means to connect said sections together to form a continuous gas passage through the sections.

4. In a combined muffler and air heater, an asbestos covered casing open at one end and provided at its opposite end with an air 105 discharge passage, and an air conducting pipe connected with said discharge passage, a heat distributing register secured to the opposite end of said pipe, a series of hollow muffler sections arranged in said casing, said sections being formed in two parts having flanged attaching edges adapted to contact with the inner periphery of the cylinder, said flanges being cut away to form an air passage, the passage of one of 115 said muffler sections being arranged at a diametrically opposite point in the casing from the passage of the adjoining muffler section whereby a circuitous air passage is formed through the casing around said sections, baffle plates secured in said sections between the flanged edges thereof, said plates having formed therein a series of 120 passages and each of said plates also having a pointed projection at its center whereby the exhaust gases entering the sections are deflected toward the passages in said plates, and means to connect said sections together to form a continuous gas passage 125 through the sections, one end section hav- 130

ing an inlet for exhaust gas and the opposite end section having an outlet for the same.

5. A combined muffler and heater comprising a casing having air and gas inlets at one end and air and gas outlets at its opposite end, hollow muffler sections arranged transversely within the casing and having flanged edges in contact with the inner walls thereof, said flanged edges being provided with air passages alternately at diametrically opposite points, means forming communication between adjacent muffler sections and between the end sec-

tions and the gas inlet and gas outlet respectively whereby a continuous gas passage is formed through the sections between the gas inlet and gas outlet of the casing, and means within each section for imparting a tortuous circulation to the gas passing therethrough. 15 20

In testimony whereof I have hereunto set my hand in presence of two subscribing witnesses.
